O. E. HUNT

AIRCRAFT

Filed Nov. 10, 1917

UNITED STATES PATENT OFFICE.

ORMOND E. HUNT, OF DETROIT, MICHIGAN, ASSIGNOR TO PACKARD MOTOR CAR COMPANY, OF DETROIT, MICHIGAN, A CORPORATION OF MICHIGAN.

AIRCRAFT.

Application filed November 10, 1917. Serial No. 201,258.

To all whom it may concern:

Be it known that I, ORMOND E. HUNT, a citizen of the United States, and resident of Detroit, Wayne County, State of Michigan, have invented certain new and useful Improvements in Aircraft, of which the following is a specification.

This invention relates to airplanes and particularly to the arrangement of the exhaust pipes of the motor relative to the airplane parts.

In the very rapid movement of an airplane through the air thin air pockets are created at various points and particularly just above the rear edge of the wings. In the present invention this fact is taken advantage of to assist in withdrawing the exhaust gases from the motor exhaust pipes.

From the above it may be observed that one of the objects of the invention is to provide an airplane in which the motor exhaust pipes lead to thin air pockets caused by the movement of the airplane.

Other objects of the invention will appear from the following description taken in connection with the drawings which form a part of this specification, and in which:

Fig. 1 is a perspective view of an airplane embodying this invention, parts being cut away to better illustrate the construction;

Fig. 2 is a fragmentary view of one of the airplane wings shown in Fig. 1 and illustrating another form of the invention; and

Fig. 3 is a view similar to Fig. 2 illustrating a third form of the invention.

Referring to the drawings, 10 represents the fuselage or body of an airplane, 11 is the propeller, and 12 represents the tail fins of the craft. The landing gear is illustrated at 13, and a pair of wings 14 are shown extending laterally from the sides of the fuselage.

Part of the wall of the fuselage is broken away at 15 to show the arrangement of the motor 16 therein. This motor is usually of the hydrocarbon type and as shown is a V type motor having four cylinders in each of the two blocks. In this motor, each of the cylinder blocks has connected to it an exhaust pipe 17 which carries off the exhaust gases from the cylinders. It will be understood that the freer the exhaust of these

gases into the atmosphere the better will be the operation of the motor, and if they could be exhausted into a vacuum the results would be better than when they are exhausted directly into the atmosphere.

It will be understood also that by the rapid forward movement of an airplane, such as herein shown, a thin air pocket or partial vacuum is created along the upper surface of the wings and particularly adjacent the rear edges of the wings. These thin air pockets are taken advantage of in the present invention by leading the exhaust pipes 17 directly to them so that the suction created by them will tend to draw the exhaust gases from the pipes. As shown, the exhaust pipe 17 from one block of cylinders leads to a point 18 adjacent the rear edge of one of the airplane wings 14 where a thin air pocket is formed as above stated, and the exhaust pipe 17 from the other side of the motor leads to a similar point adjacent the other wing.

In a second form of the invention shown in Fig. 2, the exhaust pipe 17^a extends for some distance parallel to the rear edge of the airplane wing 14 as shown at 19, and a slit or elongated opening 20 is formed in part 19 of the exhaust pipe to thereby expose a greater length of opening to the thin air pocket and increase the suction.

A somewhat similar arrangement is shown in Fig. 3 except that here the part 19^a of the exhaust pipe is provided with a series of perforations or openings 21 which furnish communication between the interior of the exhaust pipe and the thin air pocket.

Other forms may be used without departing from the spirit or scope of the invention.

Having thus described my invention, what I claim and desire to secure by Letters Patent is:—

In an airplane, the combination with a hydrocarbon motor and one of the wings of the airplane, of an exhaust pipe for the motor leading to adjacent the rear edge of said wing and exhausting into the thin air pocket caused by said wing as the airplane moves forwardly.

In testimony whereof I affix my signature.

ORMOND E. HUNT.
